INVENTOR

Emery Parker

United States Patent Office.

EMERY PARKER, OF NEW BRITAIN, CONNECTICUT, ASSIGNOR TO THE RUSSELL AND ERWIN MANUFACTURING COMPANY, OF SAME PLACE.

Design No. 3,722, dated October 19, 1869.

DESIGN FOR A SHUTTER-HOOK OR BAR

The Schedule referred to in these Letters Patent and making part of the same.

To all whom it may concern:

Be it known that I, EMERY PARKER, of New Britain, in the county of Hartford, and State of Connecticut, have invented a new and improved Design for Shutter-Hooks or Bars; and I do hereby declare that the following specification, taken in connection with the drawings making a part of the same, is a full, clear, and exact description thereof.

A A' indicate the two plates of a shutter-hook, to the former of which the hook-ended bar B is pivoted, while the latter carries the staple-stud by which the hook on the bar is held when the shutter is fastened.

The design for the two plates A A' is the same.

Each is in the general shape of a lozenge flattened at the sides. The edge is surrounded by a raised band, *a*, and a bead-moulding, *b*.

The ground may be either plain or matted.

The staple-stud C, and its imitation fellow D, on the shutter-bar, are of the same design, which is made up of a surrounding band, *c*, a four-armed cross, with intermediate ball-headed spurs radiating from a raised centre, and enclosed within a Gothic fillet, all in relief, upon a matted ground.

The shutter-bar has a raised-edge band, with the space between the two filled in with scroll-work in relief, as shown.

What I claim as my invention, and desire to secure by Letters Patent, is—

The design for a shutter-hook or bar, substantially as herein shown and described.

EMERY PARKER.
